PAINT CAN ACCESSORY

James W. Kent, Brooklyn, and Elmer P. Peters,
Richmond Hill, N. Y.

Application July 15, 1933, Serial No. 680,566

2 Claims. (CL 220—90)

This invention relates to a device to be used in connection with the ordinary standard commercial can of prepared paint or other content. The device is in the nature of a paint can attachment, so to speak, adapted to be attached to a can of paint when it is sold or which may be given separately as an attachment or accessory to facilitate the painting operation. The device may also be used as an extra sealing means to prevent accidental removal of the top of the can, but more particularly the device is designed to be used as a brush rest and scraper.

The object of the invention is therefore to provide a novel attachment for paint cans characterized by the embodiment of certain novel features such as hereinafter described and as illustrated in the accompanying drawing in which

Fig. 1 is a perspective view of the device.

Figs. 2 and 3 show modifications.

Fig. 4 illustrates the use of the device.

Fig. 5 illustrates the manner of attaching the device shown in Figure 3.

Fig. 6 shows how the device may be used as a sealing means.

Fig. 7 shows a still further modification.

In its simplest form the device consists of a bar long enough to reach diametrically across a paint can. The ends of the bar are bent downward to form legs ending in suitable feet or can engaging members which either engage the sides of the can frictionally or which may more particularly engage the bearings of the bail on larger size cans.

In either of the foregoing named cases the cross bar may be crimped or bent to correspond to the shape of the top of the can so as to be more permanently attached and serve as a sealing means or additional safety device to prevent accidental removal of the top of the can.

Referring now to Figure 7 the device consists of a bar 10 having two parallel legs 11 the ends of which are bent, formed or shaped to provide can body engaging feet or members 12. Such a device may be made inexpensively of suitable wire. The length of the bar 10 is such that it will reach diametrically across a paint can according to the size thereof. In use the device will be placed on the open can so that the bar will rest on the edges of the can and the legs will extend downward, the feet engaging the sides of the can circumferentially. If necessary the legs may be bent slightly inward for better engagement with the can as will be under-

stood. The bar will then be positioned as shown in Figure 4 and may then obviously be used as a brush rest and scraper to remove surplus paint from the brush after it has been dipped in the paint. Inasmuch as the bar is very thin, very little paint will adhere to it but will run down back into the can. This is an obvious advantage over the present practice when the paint brush is scraped against the edge of the can in which case much paint adheres to the inside of the sides of the can and is wasted. It also provides a more cleanly mode of operation. The device is easily removed when the can is to be closed. When this device is used it is of course immaterial whether the can is provided with a bail or is without a bail.

In Figure 1 the device embodies a bar 13 having legs 14 which are bent to form loops 15. This device is attached as shown in Figure 4 by raising the bail 18 of the can 16 and then pushing the loops in over the bail bearings 17. The open space 19 between the loops and the legs 14 affords a means for passing the loops inside the bail.

The modification shown in Figure 2 may be used with advantage in cases where the bail of the can may be temporarily removed by springing the bail ends outward from the bearings. In this case the loops 20 on the ends of the legs 21 are simply pushed in over the bearings and the bail may then be replaced. In Figures 1, 2 and 3 the device is shown as being made of a thin flat metal strip, but wire material may of course be used also.

The device in Figure 3 comprises a bar 23, legs 24 and looped feet 25. 26 designates a slot which extends from the one loop to the other loop. In cases where the can bail can not be removed this device may be attached as shown in Figure 5 by raising the bail so that it will extend upwardly through the said slot 26, after which the device is pushed down on top of the can and the loops pressed inward over the bail bearings.

In Figure 6 the bar 30 has legs 31 and looped feet 32. The bar is made longer than the diameter of the can so that, after the device is placed on the can, the bar may be crimped or bent as at 35 so as to draw the legs against the sides of the can while at the same time the bend 35 is pressed downward to engage the usual groove 36 provided in friction can tops 37 and thus holds the latter against accidental removal during handling and shipping. The device being made from thin flat metal or suitable wire mate-

rial is pliable or flexible enough to permit such bending engagement with the top and the edges of the can and to allow for an outward bending of the legs to detach the device and remove the top. Thereafter the device is attached for use as explained in the foregoing.

The device may be made of any suitable flat or wire material of such size, strength, dimension and pliability and flexibility so as to function as described. In all cases the device is attached relatively permanently to an open can to serve as a paint brush rest and scraper.

It should also be noted in particular in connection with the form shown in Figure 7 that the leg portions of the device may be shortened materially to an extent where it may be said that they are practically eliminated. However, such change and other changes are within the scope of the contemplated construction of the

device and intended to be included within the scope of the appended claims.

We claim:—

1. An article as described comprising a bar adapted to be placed diametrically on top of an open can above the capacity contents of the can, said can having a bail secured in bail bearings, and means at the ends of said bar adapted to engage the said bail bearings for securing the bar to the can. 5

2. An article as described comprising a horizontal bar member and a depending leg member at each end of the bar member, all of said members being slotted throughout their lengths, said leg members terminating in loops communicating with the slot in the said bar leg members. 10
